UNITED STATES PATENT OFFICE.

HENRY J. JORGENSEN, OF JERSEY CITY, NEW JERSEY.

FOUNTAIN-PEN.

1,335,341.

Specification of Letters Patent. Patented Mar. 30, 1920.

Application filed March 21, 1919. Serial No. 284,202.

To all whom it may concern:

Be it known that I, HENRY J. JORGENSEN, a citizen of the United States of America and a resident of Jersey City, in the county 5 of Hudson and State of New Jersey, have invented certain new and useful Improvements in Fountain-Pens, of which the following is a specification.

This invention relates to fountain-pens of 10 the self-filling variety, and appertains more especially to that species thereof in which the replenishment of the ink-reservoir is effected by mechanism operable endwise of the pen-barrel.

One object of the invention is to produce 15 an improved pen of the type set forth wherein the constituent parts of the filling device shall occupy a comparatively restricted space, thereby enabling the pen to be made 20 of convenient dimensions, and actually compact in structure.

Another object is the production of a 25 fountain-pen of the kind mentioned having no part that protrudes exteriorly thereof, when the pen is filled and in working condition, so that a person carrying the same may not be troubled with the clearing of an obstruction every time it is put in or 30 taken out of the pocket in the usual manner.

A further object is to provide a simple 35 construction for a pen of the character described, comprising only a few parts that can be quickly assembled or disassembled, though not liable to get out of order, and shall not prevent the renovation nor hinder 40 the renewal of any standard portion of the pen that may need to be repaired or changed from time to time.

Still another object is the provision of a 45 pen of the nature specified that shall be efficient, easy to manipulate, strong, durable, adapted to be manufactured either plain or with any approved style of ornamentation, and yet amenable to low cost of production.

Other objects and advantages of the 50 invention will become apparent as the specification proceeds.

With the aforesaid objects in view, the 55 invention consists of the novel combinations and arrangements of parts hereinafter described in their preferred embodiments, pointed out in the subjoined claims, and illustrated on the annexed drawing, wherein

like parts are designated by the same reference characters throughout the several 55 views.

In the said drawings,—

Figure I is a sectional plan of a fountain-pen embodying a convenient form of the invention, certain parts appearing in full 60 view, and others being omitted;

Fig. II is a sectional side elevation of the same embodiment of the invention, the actuating elements thereof being shown in 65 their open or operative position;

Fig. III is a similar elevation with the said elements in closed or in operative position, a part being left out;

Fig. IV is a transverse section, looking 70 into the pen toward the right-hand end thereof, as shown in the preceding views; and

Fig. V is an end view, showing the closed 75 extremity of the fountain-pen, looking at the exterior thereof, that is, toward the left-hand side of the drawing as related to the other figures.

Generally described, the improved form 80 of writing implement disclosed herein comprises, in combination with the customary parts of a self-filling fountain-pen, a deflator and manipulating means therefor of peculiar construction and operation. The

parts referred to as already in common usage 85 are the pen-stock with its nib, the feed-bar underlying the same, the collapsible ink-container thereto attached, and the barrel inclosing the latter. The deflator consists of a flexible tongue fulcrumed at one end upon a pivot-pin disposed transversely of 90 the barrel head. It is stiffened intermediately of its fulcrum and the point of flexure, and thence curves upwardly under the ink-container, to deflate it when needing to be

re-charged. A bell-crank lever is provided 95 to raise the deflator as required. This bell-crank constitutes a closure for an elongate opening made in the barrel head, and is so connected therewith that it swings in and out entirely within the projected area of 100

the barrel. The shorter arm of the bell-crank is the instrumentality employed to actuate the deflator, and it is normally spaced from the latter when the barrel is closed, so that there occurs a preliminary 105 movement or pre-travel of the arm prior to

its contact with the deflator, thereby facilitating the opening of the closure and enabling the bell-crank to be placed in the most favorable position to carry out the deflating operation.

The advantages of the invention as here outlined are best realized when all of its features and instrumentalities are combined in the one and same structure, but, useful devices may be produced embodying less than the whole.

It will be obvious to those skilled in the art to which the invention appertains, upon becoming conversant with the details thereof, that the same may be incorporated in several different constructions. The accompanying drawing, therefore, is submitted only as showing the preferred exemplification of the invention.

Referring first to Figs. I, II and III, it will be seen that the writing implement exemplified in the drawing comprises, as usual, a pen point or nib *a*, with a sublying feed-bar *b*, both of which are entered into the outer end of a pen-stock *c*. The latter has a shank *d*, fitted in the open end of a barrel *e*. A neck *f* is formed on the shank, to receive the mouth of a deflatable sack *g*, adapted to hold the ink. Thence the sack extends inwardly into the barrel *e*, toward the normally closed end or head thereof, designated by the reference letter *h*. The several elements above enumerated are found in the ordinary types of self-filling fountain-pens, and therefore no claim is made to any one among them, save in so far as they may constitute parts of legitimate combinations with the novel components of the present invention.

Transversely of the head *h* of the barrel *e*, is formed an elongated aperture *11*, the upper edge whereof, as seen in Fig. II, is shaped so as to constitute a rounded lip *12*, depending from the adjacent upper wall of the barrel, the lower or opposite wall of which is beveled, as at *13*, for a purpose that will presently appear.

A closure *16*, which may be in the shape of a bell-crank lever as shown, is provided for the said aperture *11*. The principal part of the closure is formed by the longer arm (16) of this lever, the shorter arm 17 whereof overlies the beveled edge *13* above mentioned, the bevel, it will be observed, providing a clearance for the lever, when in closed position. Fig. III.

The bell-crank lever just referred to is pivotally mounted on a pin *18*, carried in the head *h* of the barrel *e*, at right angles to the aperture *11*, previously mentioned. Figs. II, III, and IV.

Between the outer extremity of the long arm *16* of the bell-crank constituting the closure aforesaid, and the adjoining wall of the barrel *e*, is provided a locking device,

which may be in the nature of a resilient latch *19*, formed as a continuation of the said arm. This latch is adapted to take under and effect engagement with the lip *12*, when the former is pressed inward between the opposed sides of the aperture *11*. Thus held by the latch, the bell-crank affords a full closure for the apertured head of the pen-barrel, as illustrated in Figs. III, IV and V.

In order to guide the said arm *16* in its inward movement, and also impart rigidity thereto, flanges *20* are provided along the opposed lateral edges of the same. These flanges may fill approximately the angles intervening between the arms *16* and *17* of the bell-crank lever, at the opposite sides thereof, respectively, as clearly shown in Figs. II and III. Through and across the said flanges is passed the before mentioned pin *18*, that pivotally supports the bell-crank.

Upon the pin *18*, intermediate of the flanges *20*, is also pivoted an eye *23*, formed at one end of a tongue *24*, located by the under side of the ink-container *g*. The tongue *24* has a fulcrum on the pin *18*, and constitutes a presser wherewith to deflate the sack or container *g*, preparatively to filling it with ink. The connection of the tongue with the pin is independent of that of the bell-crank, and such that when the latter is in closed position, the tongue lies above and spaced away from the short arm *17*. As a consequence, this arm has a preliminary movement, exclusively its own, to perform before it can reach the under side of the tongue, whenever the bell-crank is swung open. Upon touching the tongue, it is understood, the arm *17* operates to raise the same against the sack *g*, so as to deflate it preparatory to drawing ink thereinto. The preliminary movement, or what may be termed the pre-travel, of the arm *17*, enables the arm *16*, to wit, that part of the bell-crank which constitutes the closure of this improved writing implement, to be swung out partly before any pressure is applied to the tongue, incidental to squeezing the sack *g* flat, to expel the air and produce a vacuum therein. The bell-crank lever, therefore, is placed in the best position to obtain an effective purchase upon the tongue before touching the latter, and no resistance is offered in drawing it out, other than that of the spring latch *19*. Actually, the combined bell-crank and closure can be opened without effort by a slight pull with the thumbnail, and a further movement outward will bring the tongue into contact with the sack *g*, as may be seen by referring to Figs. II and III.

The tongue *24* is stiffened so as to resist bending, close to its fulcrum and at a certain distance therefrom, before an initial

flexure takes place at the free end of the tongue. To this end, the tongue is provided with a reinforcement, which may be in the nature of a rib 25, preferably formed integral therewith. Such a rib may be produced, for instance, by a depression extending along the underside of the tongue for the major part thereof, and also in its upper face, as at 26, adjacent to the fulcrum or pivotal connection 23. See Figs. I to IV inclusive.

It will be noted that the bell-crank lever hereinabove described is arranged to swing endwise of the pen-barrel *e*, that is, within the projected area of the writing implement. There is no obstruction or protuberance whatsoever located or occurring exteriorly of the cross-sectional area of the barrel, and nothing that extends outward longitudinally of the implement, when put into condition for actual use. There is but one aperture, slot, or recess provided in the barrel, and that occupies only a small space diametral to the end or head *h*, which is closed by a smooth-faced cover at all times, except when the pen has to be refilled. The closure is held sufficiently tight by means of the resilient latch or retainer 19, which may be an inward projection of the lever arm 16, as shown, or in any other suitable manner. The bell-crank may be loosely pivoted on the same pin as the tongue, as represented, or otherwise fulcrumed, if preferred. In either case, however, the tongue 24 should be floating independently of the arm 17 of the bell-crank, to insure the pre-travel or separate initial movement hereinbefore specified. The lever being flanged sidewise, it will be noted that it affords ample protection to the pivoted end of the tongue, to the extent at least that its connection with the pivot-pin 18 is shielded laterally as well as rearwardly whenever the bell-crank is swung open, and besides the tongue is properly guided at the point of flexure by the joint action of the flanges 20 and the free, upwardly-projecting end of the short lever arm 17. Thence the tongue assumes the curve represented in Fig. II, when flexed during the operation of replenishing the deflatable reservoir with ink, as before explained.

While a certain preferred embodiment of this device has been shown and described, it will be understood that changes in the form, arrangements, proportions, sizes and details thereof may be made, without departing from the scope of the invention as defined by the appended claims.

Having described my invention, what I desire to secure by Letters Patent and claim, is:—

1. A fountain pen including a barrel, an ink sack therein, a bell-crank lever diametrically positioned on said barrel so as to

oscillate outwardly from the end thereof, a pivot for said lever disposed transversely of said end, and a deflating element for said sack actuated by one arm of the lever, the latter being arranged to swing a predetermined amount before actuating said element. 70

2. A fountain pen including, a barrel, a lever mounted to oscillate in a rearward direction opposite the end of the latter, in said barrel, and a deflator for said container fulcrumed independently of said lever in position to be actuated thereby subsequently to partial oscillation of the same. 75

3. A fountain pen including, an outer casing, a deflatable bag therein, a lever pivoted to swing within the projected area of said casing, and a pressing element for deflating said bag adapted to oscillate on the same pivot as said lever following a pre-movement of the latter. 80

4. A fountain pen, including, a barrel, a collapsible ink sack inclosed thereby, a deflating element for the latter, and an operating lever with arms of unequal lengths arranged to swing within the cross-sectional area of said barrel, the shorter arm of said lever having a partial movement previous to actuation of said element. 90

5. A fountain pen including, a barrel, an ink sack therein, a deflating element for the latter, a two-armed lever oscillatable rearwardly from said barrel, one arm of said lever being adapted to actuate said element, and means for locking the other arm of the lever to the barrel. 100

6. A fountain pen including, a barrel, an ink bag therein, a deflating element for said bag, a bell-crank lever outwardly oscillatable within the projected area of said barrel, one arm of said lever actuating said element, and a latch on the other arm of the lever serving to lock it with the barrel after actuation of said first named arm. 105

7. A fountain pen including, a barrel, an ink sack therein, a flanged lever oscillatable rearwardly outward from said barrel, and a deflating element for said sack pivoted between the flanges of said lever in position to be actuated thereby. 110

8. A fountain pen including, a barrel with a slotted head, a collapsible ink sack in said barrel, a bell-crank lever oscillatable within the slot of said head, and an element for deflating said sack, one arm of said lever being adapted to actuate said element, the other arm of the lever being arranged to cover said slot and lock with an adjoining edge thereof. 115

9. A fountain pen including a barrel, a container therein, an element capable of emptying said container of air or other fluid, a diametrically positioned lever pivoted across the end of said barrel so as to swing outward rearwardly therefrom, and a connec- 120

tion between said lever and said element whereby the latter is operated by the former.

10. A fountain pen including a casing, an ink-bag therein, a lever having its operating part disposed transversely of the rear end of said casing and arranged to swing outward rearwardly therefrom, and an element for deflating said bag flexibly connected with said lever, said element being reinforced between the free end thereof and its connection with the lever.

11. A fountain pen including a casing open at its outer end, a lever constituting an oscillatable closure for said end of the casing and capable of swinging outwardly in an axial direction therefrom, a collapsible container in the casing, and a deflating element for said container arranged for actu-

ation by one arm of said lever subsequently to a pre-movement of said arm.

12. A fountain pen including a barrel with a head having a diametral aperture, an ink-bag in said barrel, a deflating element for said bag, and a bell-crank lever pivoted near one end of the barrel so as to swing rearward outwardly therefrom, one arm of said lever being capable of closing the aperture in said head and engaging with an adjacent part thereof, the other arm of the lever being arranged to overlie an opposite portion of the aperture in spaced relation to said element, whereby the latter named arm may have a pre-movement prior to actuating the element.

HENRY J. JORGENSEN.

It is hereby certified that in Letters Patent No. 1,335,341, granted March 30, 1920, upon the application of Henry J. Jorgensen, of Jersey City, New Jersey, for an improvement in "Fountain-Pens," an error appears in the printed specification requiring correction as follows: Page 3, line 75, claim 2, before the word "in" insert the words *a collapsible ink container*; and that the said Letters Patent should be read with this correction therein that the same may conform to the record of the case in the Patent Office.

Signed and sealed this 20th day of April, A. D., 1920.

[SEAL.]

M. H. COULSTON,
Acting Commissioner of Patents.
